Specification for Design.

Patented Mar. 14, 1922.

Application filed August 16, 1920. Serial No. 403,955. Term of patent 3½ years.

To all whom it may concern:

Be it known that I, ALBERT E. MURPHY, a citizen of the United States, residing at Helena, in the county of Lewis and Clark and State of Montana, have invented a new, original, and ornamental Design for an Attachment for Hand Bags, of which the following is a specification, reference being had to the accompanying drawing, in which a perspective view of the design is shown.

I claim:

The ornamental design for an attachment for hand bags, as shown.

In testimony whereof I affix my signature.

ALBERT E. MURPHY.
